[57] CLAIM

The ornamental design for a conveyor cleat, as shown.

DESCRIPTION

FIG. 1 is a perspective view of a conveyor cleat showing my new design;

FIG. 2 is a top plan view;

FIG. 3 is a side elevational view;

FIG. 4 is a front elevation view;

FIG. 5 is a side elevational view of the opposite side from the side shown in FIG. 3;

FIG. 6 is a rear elevation view; and

FIG. 7 is a bottom plan view thereof.
